UNITED STATES PATENT OFFICE.

FORREST M. MAHAN, OF YUMA, ARIZONA.

OIL-BURNER.

1,146,006.

Specification of Letters Patent. Patented July 13, 1915.

Application filed October 23, 1914. Serial No. 868,249.

To all whom it may concern:

Be it known that I, FORREST M. MAHAN, subject to the King of England, residing at Yuma, in the county of Yuma and State of Arizona, have invented a new and useful 5 Oil-Burner, of which the following is a specification.

This invention relates to oil or hydro-carbon burners.

10 An object of the present invention is to provide a novel oil burner in which a perfect mixture of steam and oil will be had prior to the issuing of the same from the burner mouth or discharge outlet.

15 A further object is to provide a unique oil burner including inner and outer pipes for the separate conduction of steam and oil and provided with peculiar coöperating discharge outlets, which may be adjusted 20 relatively to one another for the most effective operation of the device.

Another object is to provide a burner composed chiefly of plumbing fittings in order that the burner will be simple and cheap 25 to construct, and at the same time will be exceedingly efficient in service.

With the foregoing and other objects in view which will appear as the description proceeds, the invention resides in the combination and arrangement of parts and in the details of construction hereinafter described and claimed, it being understood 30 that changes in the precise embodiment of the invention herein disclosed, can be made within the scope of what is claimed, without departing from the spirit of the invention.

In the drawings accompanying this specification and forming a part thereof, the preferred embodiment of my invention has 40 been illustrated.

In said drawings:—Figure 1 is a view in longitudinal section of the improved oil burner, parts being broken away. Figs. 2, 3 and 4 are cross sections taken on the lines 45 2—2, 3—3 and 4—4, respectively, of Fig. 1. Fig. 5 is a longitudinal section of a modified form of oil and steam nozzles. Fig. 6 is a cross section taken on the line 6—6 of Fig. 5. Fig. 7 is a front elevation of the 50 modified form of burner nozzles. Fig. 8 is a cross sectional view of another modification.

In carrying out the invention, there is provided a pair of concentrically arranged horizontal inner and outer pipes 5 and 6, 55 respectively, connected to and communicating with the oil and steam supply pipes 7

and 8, respectively. To this end, one end of a T-coupling 9 is engaged to the inlet end of the pipe 5, and a plug or cap 11 is engaged to the other end of the T-coupling. 60 The oil supply pipe 7 is connected to the arm of the T-coupling and the pipes 6 and 8 are connected through the medium of the plug 11.

Outer and inner upstanding nozzles or 65 pipes 12 and 13 are connected to the outlet ends of the pipes 5 and 6, respectively, by means of outer and inner elbows 14 and 15, respectively. The nozzles form extensions of the pipes 5 and 6. The upper or free ends 70 of the nozzles are threaded as at 16 and 17, respectively, and upon which are engaged the respective outer and inner caps 18 and 19.

Threaded upon the lower portion of the 75 inner steam nozzle 13 is a flared annular deflector 20, whose rim extends upwardly and outwardly away from the steam nozzle 13 toward the walls of the oil nozzle 12. Ports or apertures 21 are provided in the nozzle 80 13 within the deflector 20 for directing jets of steam against the inner walls of the deflector so as to impinge thereagainst and to be deflected thereby upwardly within the nozzle 12. 85

The steam pipe 6 is provided in its top with a diagonal or inclined port or aperture 22 adjacent the nozzles for directing a stream or jet of steam in a direct diagonal line upward into the nozzle 12. One side 90 of the nozzle 12 is provided with an arcuate transverse outlet slot or mouth 23, and the adjacent side of the nozzle 13 is provided with a similar slot 24 coöperating with and relatively smaller than the slot 23. 95

In order to properly adjust and maintain in position, the nozzles 12 and 13, the cap 18 is provided with a central threaded aperture 25 through which is threaded an adjusting or jam bolt 26. The latter extends 100 down upon and seats or impinges within a central depression 27 formed in the cap 19. Coacting with the aforementioned adjusting means are three radial set screws or bolts 28 threaded through the walls of the pipe 105 5 and contacting with the inner pipe 6.

In operation, it being understood that the supply pipes 7 and 8 are connected to suitable sources of oil and steam, respectively, the steam after passing through the pipe 6 110 and nozzle 13 will be discharged through the outlet slot 24 in a fan or film-like stream,

which will pass through the outlet slot or mouth 23 of the nozzle 12. The steam will also be discharged in a stream or jet through the aperture 22 diagonally upward into the nozzle 12, to atomize the oil, and thoroughly commingle the atomized oil and steam. Similarly, steam will be discharged through the apertures 21 of the nozzle 13 and will be deflected upwardly by the deflector 20, to assist in the atomization and admixture of the oil or liquid fuel, prior to the discharge of the vapor through the slot 23 by the suction created when the steam is discharged through the slot 23 from the outlet slot 24 of the nozzle 13. The oil in entering the pipe 5, and surrounding the heated steam pipe 6, will become heated, to assist in the atomization of the oil before reaching the outlet. The flame being of fan-like form, will spread throughout a considerable area, for increasing the heating effect and extent of the flame.

The steam nozzle 13 may be adjusted and held within the oil nozzle 12, by loosening the screws 26 and 28, and retightening the said screws properly for raising and lowering and centering the nozzle 13 within the nozzle 12. In this manner, should the nozzles 12 and 13 become disarranged, due to unavoidable reasons, such as the warping of the parts under the heat to which the device is subjected, the parts may be readjusted, in order that the burner will operate most effectively.

In the modified form of burner nozzles illustrated in Figs. 5 to 8, inclusive, outer and inner elbows 14' and 15' are provided, which are attachable to the outer and inner oil and steam pipes, respectively, as suggested in Fig. 1. Outer and inner nozzles 12' and 13' are threadedly engaged to the elbows 14' and 15', respectively, and have the outer and inner heads 30 and 31, respectively, at their upper ends. The heads 30 and 31 of the nozzles are provided with the coöperating arcuate outlet slots 23' and 24', respectively. The head 30 is provided with a continuous flange or lip 32 surrounding the outlet slot 23', and the said lip is flared or fan shaped to spread the flame effectively, and to facilitate the operation of the burner. The inner nozzle 13' is provided with upwardly inclined or diagonal ports or apertures 21' for the outlet of steam into the

nozzle 12' for agitating and atomizing the oil.

In order to adjust and hold the nozzle 13' within the nozzle 12', a pair of adjusting screws 34' are threaded through the elbow 14' and have their tips engaging the inner elbow 15', and an adjusting screw 35 is threaded through the top of the head 30 and impinges against the top of the head 31, so that by adjusting the screws 34' and 35, the inner nozzle 13' may be adjusted and held properly within the outer nozzle 12'.

In the form illustrated in Fig. 8, the lip 33 around the outlet slot, has its ends provided with the portions 34 which restrict the extent of the flame.

Having thus described the invention, what is claimed as new is:—

1. A hydrocarbon burner comprising horizontal outer and inner fuel and steam pipes, respectively, upturned outer and inner nozzles connected to the outer and inner pipes, respectively, the nozzles having coöperating transverse outlets, an adjusting screw carried by the upper end of the outer nozzle and bearing against the upper end of the inner nozzle, and adjusting screws threaded through the outer pipe and engaging the inner pipe.

2. A hydrocarbon burner comprising outer and inner fuel and steam pipes, respectively, and outer and inner nozzles connected to the outer and inner pipes, respectively, and extending angularly therefrom, the said inner pipe having a diagonal aperture adjacent the nozzles for directing a jet of steam in a direct diagonal line into the outer nozzle.

3. A hydrocarbon burner comprising outer and inner fuel and steam nozzles, respectively, having coöperating outlets, and an annular flared deflector secured upon the inner nozzle, the inner nozzle having apertures within the said deflector for directing jets of steam against the inner walls of the deflector so as to impinge thereagainst and to be deflected thereby.

In testimony that I claim the foregoing as my own, I have hereto affixed my signature in the presence of two witnesses.

FORREST M. MAHAN.
